United States Patent Office

Des. 212,665
Patented Nov. 5, 1963

212,665

DISPLAY SIGN

James E. Latimer, 208 N. Lafayette Blvd.,
Warren, Mich. 48089

Filed Aug. 2, 1967, Ser. No. 3,038

Term of patent 14 years

(Cl. D96—12)

FIG. 1

FIG. 3

FIG. 2

FIG. 4

FIG. 1 is a front elevational view of a display sign embodying my new design.

FIG. 2 is a rear elevational view thereof.

FIG. 3 is a right end elevational view thereof.

FIG. 4 is a left end elevational view thereof.

The dominant features of my design reside in the portions shown in full lines.

I claim:

The ornamental design for a display sign, as shown and described.
